(57) **CLAIM**

The ornamental design for a hook for hanging, as shown and described.

DESCRIPTION

FIG. 1 is a front isometric view of a hook for hanging showing the design.

FIG. 2 is another front isometric view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The shading lines shown in the drawings represent the approximate three-dimensional contour of the claimed design and are not intended to indicate surface decoration. The dashed line in the drawings represents or bounds a portion of the design that is not claimed.
